UNITED STATES PATENT OFFICE.

ALEXANDER SWANSON, OF LIVINGSTON, MONTANA TERRITORY.

GEARING FOR OPERATING PUMPS.

SPECIFICATION forming part of Letters Patent No. 395,298, dated December 25, 1888.
Application filed September 6, 1888. Serial No. 284,700. (No model.)

To all whom it may concern:

Be it known that I, ALEXANDER SWANSON, a citizen of the United States of America, residing at Livingston, in the county of Park and Territory of Montana, have invented certain new and useful Improvements in Gearing for Operating Pumps; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention has relation to improvements in gearing for operating pumps.

The essential feature of my invention is the employment of self-reversible mechanism to be used in connection with a pump-piston, wherein by turning a crank-handle continuously in one direction the piston and plunger of the pump will be alternately raised and lowered.

With this end in view my invention consists in a novel arrangement and combination of mechanical devices, as will be more fully hereinafter described and claimed.

I have illustrated my invention by the construction shown in the accompanying drawings, wherein like letters of reference are used to indicate similar parts, and in which

Figure 1 is a sectional elevation of my improved pump. Fig. 2 is a section on line *xx* of Fig. 1, showing one of the gears in top plan view.

A indicates the vertical side strips of the supporting-frame, having lower cross-strip, *A'*, and from the top of one beam, *A*, to one side of the other a strip, *A²*, runs and is secured. Below the strip *A²*, between the side strips, a strip, *A³*, is mounted, having an aperture therethrough and a centrally-apertured screw-threaded plate, *d²*, secured to the under side thereof. One of the beams *A* is considerably longer than the other and forms a support for the upper structure and mechanism. To the outside of the upper end of the shorter strip, *A*, a horizontally-arranged strip, *a²*, is secured and held in position by the brace *a³*, secured to the

outer end thereof and to the said shorter strip. From the outer end of the strip *a²* a strip, *a'*, extends vertically upward to a flex with the top of the longer strip, *A*, the upper ends of said strips *a'* and *A* being connected by a cross-strip, *a*. A short distance above the cross-strip *A²* a cross-strip, *A⁴*, is secured at its ends to the strips *a'* and *A*. This frame-work constitutes the support for the mechanism.

Running across the upper part of the frame, and having bearing in the strips *A* and *a'*, is a shaft, *B*, the one end of which extends out beyond the strip *a'* and has a crank, *b*, secured thereon. Upon this shaft *B* two bevel gear-wheels, *B'*, are keyed, having their beveled faces arranged opposite to each other. Only one-half of each of these wheels has teeth cut thereon, and are so arranged that the teeth on one are opposite to the blank space on the other. Stepped in the strip *a²*, and extending vertically upward through strip *A⁴*, is a short shaft, *C*, having a beveled pinion secured on its upper end, which meshes alternately with the teeth on the wheels *B'*.

On shaft *C*, between the beams *A⁴*, *a²*, and *A²*, a large gear-wheel, *C'*, is keyed, and is in continual mesh with a pinion, *D'*, mounted on a vertical shaft, *D*. The shaft *D* has a screw or worm surface, *d'*, thereon, which passes through and coacts with the block *d²* on strip *A²*. The upper end of said shaft passes through the strips *A²* and *A⁴*, and is formed with a slot, *d*, which is engaged by a spline, *d¹*, formed with pinion *D'*. The lower end of the said shaft is connected to the upper yoked end, *e*, of a piston-rod, *E*, by a nut, *d³*. It will be understood that the said piston is adapted to be attached to the plunger of a pump. In order that shaft *B* may be run by power other than by crank *b*, a pulley, *b'*, is fixed thereon, which may be encircled by a driving-belt. As shown, the plunger is rising in the cylinder and the shaft *B* is revolved by crank *b* in the direction of the arrow placed therearound. As shown, the left-hand gear *B'* is in mesh with the wheel *C'*, said wheels running in the direction of the arrows. This motion is transmitted through gear *C'* to pinion *D'* on shaft *D*. This motion will be continuous so long as the teeth of the said left-

hand gear B' are in mesh with the teeth of gear C'. By this motion the shaft D rises through the medium of the screw-surface d' thereof coacting with the block d², and consequently the plunger F is raised in chamber G, acting upon the valves thereof, as will be readily understood. When the teeth of the left-hand gear B' cease to be in mesh with wheel C', the parts are so timed that said wheel C' is immediately engaged by the teeth of the right-hand gear B' and the motion of the parts, as above set forth, reversed, thus forcing the plunger downward in the cylinder. It will be understood that the shaft B is revolved but in one direction continuously, the reversal of motion being controlled by the gears B'. As the shaft D rises and lowers, it moves through gear D', mounted thereon, which is allowed through the spline-and-groove connection of said parts. The said wheel D' revolves at the same time that the shaft D is passing therethrough. The space between strips A² and A⁴ is of such width as to cause a continual mesh of the said wheel D' with gear C². By this means any tendency to disengagement of said wheels is prevented and a continuous revolution in either direction is sustained, and the general operation of the pump thereby made effective. Any tendency of the shaft D to slip is also avoided through the positive engagement of the screw-surface d' thereof with the set-block d² on strip A³. Thus when a cessation of motion of shaft B is had the plunger remains stationary in the pump-cylinder at the point of elevation or depression it has reached when the motion of the mechanism has ceased.

Having thus described my invention, what I claim as new, and desire to secure by Letters Patent is—

1. In the mechanism herein set forth, the combination of the supporting frame-work, a revoluble automatically-reciprocating screw-threaded shaft adapted to be attached to the piston of a pump, and a drive-shaft adapted to be revolved continuously in one direction having self-reversing gear thereon; in connection with the said revoluble shaft, substantially as described.

2. In the mechanism herein set forth, the combination of the frame-work, a revoluble automatically-reciprocating vertical screw-threaded shaft adapted to be attached to a pump-plunger, and gearing in connection with and reversibly operating said shaft, substantially as described.

3. In the mechanism herein set forth, the combination, with the plunger, of a shaft attached thereto having a screw-surface thereon engaging with a set-block and having a slot in its upper end, a gear-wheel on said shaft having a spline engaging the slot thereof, and the gearing for operating said parts, substantially as described.

4. In the mechanism herein described, the combination, with the automatically-reciprocating revoluble vertical shaft attached to a plunger and having a gear thereon, of the shaft B, adapted to be continuously revolved in one direction, having gear-wheels B' keyed thereto, with teeth formed thereon, as set forth, and the intermediate gearing between said wheels B' and the gear on the vertically-adjustable revoluble shaft, substantially as described.

5. In the mechanism herein set forth, the combination of the frame-work, the shaft B, adapted to be revolved in one direction, the gears B' thereon with teeth cut in one half of said wheels and arranged opposite the blank space of the other, the short vertical shaft C, carrying a gear, C', on the upper end thereof meshing alternately with the teeth of gears B', and also having a gear, C², thereon, the gear D', having a spline meshing with the gear C², and the shaft D, having a groove, d, in its upper end engaged by the spline of gear D' and formed with a screw-surface, d', coacting with a set-block, d², the said shaft being adapted to be secured to a pump-piston, substantially as described.

In testimony whereof I affix my signature in presence of two witnesses.

ALEXANDER SWANSON.
